STEM

Julius Harris and Edward Harris, Chicago, Ill.

Application January 8, 1937, Serial No. 119,692

4 Claims. (Cl. 131—192)

Our invention relates to smokers' articles, and has among its objects and advantages the provision of an improved stem.

An object of our invention is to provide a stem including two parts hingedly connected together and in which the hinge is so designed as to lie within the contour of the stem structure.

Another object is to provide a stem including hinged parts in which novel means is provided for latching the parts in connected relation.

A further object is to provide a pipe stem so constructed as to facilitate cleaning and folding of the parts into compact relation for packaging and transportation purposes.

Another object is to provide a pipe stem made up of hinged parts including means for latching the parts in connected relation in which the latch operates automatically for breaking and latching purposes in response to forces applied to the stem for pivoting the parts about the axis of the hinge.

In the accompanying drawing:

Fig. 1 is a perspective view of a pipe embodying our invention;

Fig. 2 is a longitudinal sectional view of the pipe;

Fig. 3 is an enlarged sectional detailed view of the hinge and latch features;

Fig. 4 is a sectional view along the line 4—4 of Fig. 3;

Fig. 5 is a sectional detail view illustrating the manner in which the stem parts may be broken;

Fig. 6 is a sectional detail view of a different form of latch; and

Fig. 7 is a sectional view along the line 7—7 of Fig. 6.

In the embodiment selected to illustrate our invention, we make use of a pipe comprising the usual bowl 10 and stem 12. The stem 12 comprises the usual stem part 14 formed integrally with the bowl 10 and a mouth piece 16. A hinge 18 pivotally connects the mouth piece 16 with the stem part 14.

Specifically, the hinge 18 comprises a flange 20 and a tubular extension 22 pressed into the enlarged bore 24 in the stem part 14. In Fig. 2, the flange 20 is arranged in abutting relation with the end of the stem part 14, which part is provided with the conventional bore 26 which establishes communication between the bowl 10 and the tubular extension 22.

A similar tubular extension 28 is pressed into the bore 30 in the mouth piece 16. The tubular extension 28 carries a flange 32 which lies adjacent the end of the mouth piece and adjacent

the flange 20 in the normal position of the mouth piece, as illustrated in Figs. 2 and 3. A bore 34 is provided in the mouth piece 16, which bore communicates with the extension 28, which in turn communicates with the tubular extension 5 5 22.

To pivotally connect the flanges 20 and 32, each flange is provided with a recess 36 for the reception of a link 38. This link lies within the recesses 36 with its outer face terminating flush 10 with the outer face of the stem part 14 and mouth piece 16. We provide the link 38 with two holes 40 for the reception of pins 42 which extend through openings 44 in the flanges 20 and 32. The ends of the pins 42 are shaped at 46 to conform to the cross sectional contour of their respective flanges.

Link 38 is loosely mounted on the pins 42 so that the hinge 18 includes two axes, whereby the mouth piece 16 may be folded back upon the stem part 14, as illustrated in Fig. 2. We prefer to position the hinge 18 in such a manner as to bring the end 48 of the mouth piece 16 into holding relation with a spring clip 50 and anchored to the bowl 10. Fig. 2 illustrates the mouth piece in dotted lines in its folded position.

Referring to Fig. 3, we provide the flange 20 with a short tubular extension 52 having an outside diameter fitting snugly within the inside diameter of the tubular extension 28. Extension 52 is provided with a groove 54 in its outer wall for the reception of a split spring element 56. The groove 54 extends completely around the extension 52, while the spring element 56 substantially encircles the extension, but its ends are spaced as at 58 to permit inward flexure of the spring element. According to Fig. 3, the spring element 56 has an outside diameter larger than the outside diameter of the extension 52 and is arranged to snap into a groove 60 in the inner face of the tubular extension 30 when the mouth piece 16 is moved into axial alignment with the stem part 14, as illustrated in Fig. 3.

In Figs. 3 and 5, we illustrate the flange 32 as being cut away at 62 to provide clearance for 45 the end of the extension 52. The end of the extension 52 may be rounded, as at 64, to provide additional clearance.

In operation, the latch comprising the extension 52, the groove 60 and the spring element 36 50 operates to unlatch automatically when the mouth piece 16 is bent upwardly and backwardly in the direction of the bowl 10. The relation between the spring element 56 and the groove 54 is such as to effectively hold the parts of the 55

stem in connected relation with the flanges 20 and 32 arranged in abutting relation. Because of the snug fit between the extension 52 and the tubular extension 30, an effective air seal is provided. The latch feature operates automatically by merely pivoting the stem 12 toward its axial alignment with the stem part 14.

Our hinge 18 lies within the contour of the stem 12 so as to eliminate projecting parts. The hinge is so constructed as to bring the flanges 20 and 32 in pressure relation, while the spring element 56 maintains the two flanges in such pressure relation. In bringing the hinge and the latch structure within the contour of the stem proper, we provide a construction which greatly enhances the artistic aspects of the pipe. In providing a latch such as that described, we eliminate the necessity for manually actuated elements which must be operated to precondition the hinge structure to permit breaking or latching of the stem parts.

Figs. 6 and 7 illustrate a slightly different form in which the flange 66 corresponding to the flange 20 is provided with a tubular extension 68 slotted at 70 to provide four spring elements 72 having curvatures 74 arranged to lie within the groove 76 in the flange 78, which corresponds to the flange 32. With the spring elements 72 positioned within the groove 76, as illustrated in Fig. 6, the frictional relation between the curvature 74 and the groove is such as to effectively hold the stem part 80 and the mouth piece 82 in connected relation. The circular part 84 has pressure relation with the flange 78 at 86 so as to establish an air-tight connection. The hinge 84 is of the same construction as the hinge 18.

Without further elaboration, the foregoing will so fully explain our invention that others may, by applying current knowledge, readily adapt the same for use under various conditions of service.

We claim:

1. In a smoking pipe, a stem part having a bore, a flanged tubular element anchored within said bore with the flange positioned exteriorly thereof, a mouthpiece having a bore, a tubular member anchored within the bore in the mouthpiece with its flange positioned exteriorly thereof, said two flanges normally lying in abutting relation, a hinge connecting the two flanges, to

permit the mouthpiece to be pivoted with respect to the stem part, a resilient element carried by one of said flanges, and means carried by the other of said flanges and cooperating with said resilient element for releasably latching the mouthpiece in connected relation with the stem part, said resilient element and said means lying within the contour of the mouthpiece, and said hinge lying within the contour of said stem part and the mouthpiece.

2. A smoking pipe comprising a bowl having a stem, a mouthpiece hingedly connected with the stem, means housed within the contour of the stem and the mouthpiece for holding the two in operative relation when the mouthpiece is moved to a position in axial alignment with the stem, said mouthpiece being foldable back upon the stem, means cooperable on the bowl and the free end of the mouthpiece for frictionally holding the mouthpiece in folded relation with the stem, said second means comprising a resilient element attached to the bowl, to have pressure relation with the free end of the mouthpiece, the hinge connection between the mouthpiece and the stem being of such construction and located at such a distance from said means as to cause the mouthpiece to be held in frictional relation with said means.

3. In a smoker's article, a stem comprising a first part provided with an extension, a spring element carried by said extension, a second stem part, a hinge connection between the first part and the second part, said hinge comprising a link pivoted at one end to the first part and at its other end to the second part, said second part being provided with a bore having a groove, said spring element being arranged to snap into said groove when the first and second parts are moved into axial alignment.

4. In a smoker's article, a stem comprising a first part and a second part, a slotted extension carried by the first part, said second part being provided with a bore having a groove, said slotted extension having curved elements arranged to lie within said groove when the first and second parts are arranged in axial alignment, and a hinge connecting the first and second parts.
